PACKAGE FOR WATCH MAIN-SPRING

William Ogle Bennett, Jr., Bayside, Frederick De Merle Lower, Elmhurst, and George Ott, Jr., New Hyde Park, N. Y., assignors to Bulova Watch Company, Inc., Flushing, N. Y., a corporation of New York

Application May 6, 1954, Serial No. 428,032

1 Claim. (Cl. 206—70)

The present invention relates to an improved container or package for small articles and relates more particularly to the packaging of watch main-springs.

It is well recognized that the maintenance of time pieces, as for example watches, by the replacement of individual parts is an important phase of the industry. The manufacturer of a given line of watches makes available to its distributors, or to others who repair watches, a supply of watch parts for replacement. An important item in this line of activity is the replacement of the watch main-spring. Ordinarily a main-spring, in unwound condition, as usually supplied, is difficult to handle and to identify as to size for use in a particular size watch.

It has been proposed to supply the springs in a container in which the springs are loosely wound. When used as a replacement such partially wound packaged springs, as in the case of the entirely unwound springs, must be properly wound in what is termed a main spring winder for insertion into a watch main-spring barrel.

Winders for this purpose are well known and widely used in the industry and are made in a range of sizes to meet the dimensions of various size watch main-spring barrels. The winders are in some cases provided with movable jaws to increase or decrease the diameter of the barrels to conform with the barrels of different watches, thus giving a wide range of variation to the winders. Each winder is provided with an ejector for forcing the wound watch spring into the barrel of a watch requiring a main-spring replacement.

In accordance with the present invention the operation of replacing a watch main-spring is simplified to the extent of avoiding the time consuming handling and winding of a replaceable main-spring and in correlating the spring and a container so as to facilitate the selection of proper spring for a given size watch, and further in providing a container so constructed and arranged as to cooperate with means for transferring a wound main-spring from its package or container directly into operative position in a watch main-spring barrel.

It is an object of the present invention therefore to supply main-springs wound and ready to be inserted into a watch main-spring barrel.

Another object of the invention is to provide a shipping and storage container whereby a wound main-spring is so positioned as to be readily ejected from the container directly into the main-spring barrel of a watch.

Another object of the invention is to provide a watch part container so constructed and arranged as to cooperate with a tool for ejecting the part from the container through a preselected path.

Another object of the invention is to provide a part container in the form of an apertured plate or disk and in tensionally engaging a wound main-spring with the perimeter of said aperture.

Another object of the invention is to provide a main-spring container in the form of a flat plate or disk-like body apertured to receive a wound main-spring and provided with indicia to indicate the size of the wound spring and having means for supporting the containers in orderly arrangement with the indicia exposed for ready inspection.

2

Another object of the invention is to provide a tool having a plurality of ejector members of different sizes for ejecting springs of different sizes from containers.

Another object of the invention is to provide a tool having a plurality of ejector members of different sizes and colors for ejecting springs of different sizes from containers of corresponding colors.

Other objects and advantages of the invention will be more fully understood by reference to the following description together with the accompanying drawing in which:

Fig. 1 is a full size plan view of a watch main-spring in normal unwound condition;

Fig. 2 is a plan view of a full size watch main-spring barrel;

Fig. 3 is a perspective full size view of a container or package for a watch main-spring as constructed in accordance with the present invention;

Fig. 4 is an enlarged view of one side of the container shown in Fig. 3 with a coiled main-spring in the container;

Fig. 5 is a view similar to Fig. 4 but showing the opposite side of the container;

Fig. 6 is a view taken in line VI—VI in Fig. 4;

Fig. 7 is a perspective view of a transverse section of the container without a coiled main-spring therein;

Fig. 8 is a transverse cross sectional view of a container in position for the transfer of a coiled main-spring into a watch main-spring barrel;

Fig. 9 is an enlarged cross sectional view of a watch main-spring barrel with a main-spring in position;

Fig. 10 is a perspective view of a cabinet partitioned to provide compartments for supporting packaged mainsprings;

Fig. 11 is an enlarged view taken on line XI—XI in Fig. 10, and;

Fig. 12 is a perspective view of a tool used to eject coiled main-springs from containers.

The present invention makes possible the practical transportation, storage and application of coiled watch mainsprings.

A watch main-spring 10, when in its normal form, as is shown in Fig. 1, is of generally S-shape form and must be wound into a spiral of relatively small diameter to be transferred into a watch main-spring barrel 12. This barrel as shown is part of a watch movement and is in the form of a circular cup having an annular wall 13, a bearing for a barrel arbor and gear teeth 15 to engage a center wheel pinion (not shown) which is part of a watch movement.

The present container or package is preferably in the form of a plate member or disk 16, and may be generally rectangular as shown or may be circular. When referred to hereinafter the term plate, disk or chip is intended to include a member which may be either circular or non-circular. This plate member is provided with an aperture or passage 17 to receive a coiled mainspring 18.

The plate-member may be made of any suitable moldable material and it has been found practical to form the plate-members from polystyrene which makes possible the convenient and practical use of a variety of colors for purposes to be hereinafter set forth.

As stated, the plate member 16 is provided with an aperture or passage 17. The wall 19 of this passage is, as shown, in the form of a hexagon, thus the six sides of the wall serve to provide an enclosure for a wound main-spring 18 conditioned and ready to be inserted into a watch main-spring barrel.

When positioned in the passage 17 the spring being coiled as a spiral tends to expand or unwind and make

frictional tangential contact with the sides of the passage. With this arrangement the contacting surfaces between the spring and the passage wall are separated by what may be termed channels or grooves, the purpose of which is to provide for the use of an ejector tool 20 having a maximum diameter greater than the maximum diameter of the wound main-spring.

The tool 20 is in the nature of a plunger or ejector in the form of a hexahedron to slidably fit the passage 17. The hexagonal wall 19 of passage 17 of the plate member is disposed intermediate an annular relatively shallow step or guide shoulder 21 and what may be termed the front surface 22 of the plate member.

The opposite or rear surface 23 is provided with an annular step or shoulder 24 of appreciable depth to receive the annular wall 13 of a watch main-spring barrel 12. The watch main-spring barrel, and plate member 16, are positioned in axial alignment with the passage 17 to receive a coiled spring when the latter is engaged by a tool and ejected from the plate member into the watch main-spring barrel.

From the foregoing it will be understood that the present invention provides a container so constructed and arranged as to receive a main-spring in wound condition ready to be transferred into a watch main-spring barrel. When the transfer is to be made the plate member by reason of the step or shoulder 24 cooperates with the main-spring barrel to adjust the parts, including the tool or punch 20, into axial alignment. The parts thus cooperate to effect and simplify the loading of a wound main-spring, into a watch main-spring barrel.

After a spring has been removed from a container, the container may be returned to the supplier for refilling or may be otherwise disposed of or destroyed. It has been found in practice that by the use of a plastic plate member the cost is not a factor and after having served their purpose the containers are disposed of as in the case of any package used for shipping purposes.

As explained above the present package or main-spring container may be of any selected configuration. As shown the plate member 16 is of a thickness greater than the width of the wound spring and therefore the opposite sides 22 and 23 are free from protuberances and may be packed or stacked with economy of space. Furthermore opposite edges 26 and 27 are beveled or sharp edged to be received in slots 28 and 29 of a partitioned rack 31 (see Fig. 10). As shown the rack or file case may be provided with a plurality of compartments to receive a group of containers of different colors as red, blue, green, yellow, ivory and black.

Each color may represent a group of containers for wound springs. In cases where a greater number of groups of one color than another is to be kept in stock the rack may have extra sections filled by plate members of a single color as for example ivory as indicated.

From the above it will be evident that a plurality of each of a different size wound main-springs may be stocked. As indicated six different sizes are generally required. Inasmuch as the apertures or passage 17 of the different containers differ in diameter it is necessary to provide a tool to meet each condition, and as shown in Fig. 12 a multiple tool 33 may be provided. This tool has a hub 34 from which six ejector members or tools are secured to and are disposed in radial relation to the hub. This multiple tool may be supplied to meet the requirements of the containers of different colors. Each color represents a group of springs of different types or sizes identified by a marking and the tools proper which extend from the hub 34 may be of different colors to conform to the colors of the several groups. Thus a tool of a given color will serve to eject coiled springs from containers of a similar color although, as stated, the springs in containers of the same color may differ in size or type.

It is obvious that if desired the groups of containers may have a common marking instead of a color and the tools may be marked accordingly.

As above described the container or package is so formed as to provide a wall having spaced apart surfaces for contact with the outer annular surface of the wound spring to permit a contacting surface of a tool to extend radially beyond the said annular surface of the spring whereby a positive contact is made with all the coils of the wound spring. Although the spring contacting surfaces of the passage are in the present case in the form of a hexagon it is to be understood that any suitable configuration may be used. Obviously the grooves or channels which surround the positioned wound spring may be of any selected form to meet the requirement of having portions of the tool surface extend beyond the outer surface of the coiled spring.

It has been found that when the passage is hexagonal or polyhedral and a tool in the form of a polyhedron is employed, satisfactory results are obtained. If desirable, the individual surface areas of the passage, which contact with portions of the wound spring, may be curved to conform with the curvature of the surface of the spring.

On the other hand if desired the passage 17 may be cylindrical and the tool of cylindrical form to slidably fit the passage for movement as a plunger in the passage to engage and eject a wound spring.

In either case the container is not only so constructed and arranged as to serve to transport springs but mechanically cooperates with both tool and watch main-spring barrel for the transfer of a wound main-spring into the watch main-spring barrel.

Although a preferred embodiment of the invention is shown and described herein it is to be understood that modifications may be made therein without departing from the spirit and scope of the invention as set forth in the appended claim.

What is claimed is:

40 A package of a watch main-spring comprising a plate member of predetermined thickness greater than the thickness of the watch spring inserted therein, said plate member having opposite parallel faces defining the said thickness thereof, said member having a transverse aperture therethrough with opposite ends of said aperture opening one through one of said member faces and the other through the other one of said member faces, and both of said ends of the aperture having circular contour configurations of which one has greater diameter than the other and an intermediate portion of said aperture having a polyhedral contour configuration the diameter of an included circle tangential to the facets thereof being less than the diameter of either of said circular ends of the aperture, and the thickness of said intermediate polyhedral portion of said aperture conforming to the thickness of the watch spring whereby said watch spring is entirely within said intermediate polyhedral portion of said aperture and inwardly from both of said member faces.
